CAN FEEDING APPARATUS

George W. Chalmers, Summit, Ill., assignor to
International Patents Development Company,
Wilmington, Del., a corporation of Delaware

Application April 10, 1933, Serial No. 665,392

18 Claims. (Cl. 113—115)

This invention relates to an apparatus for feeding cans, can bodies or other receptacles to a machine for performing some operation thereon; specifically, in the case of the apparatus herein shown and described for feeding cans to a machine for securing to the heads of the cans, caps to close filling openings in such heads. That is to say, the cans are filled through circular openings surrounded by upstanding flanges, caps are placed over said openings and the cans are then transferred to a machine for seaming or crimping the caps to the flanges so as to effect permanent sealed closures. This invention relates to apparatus for making this transfer.

Obviously the can feeding apparatus with which this invention is exclusively concerned, is not limited to the use of the apparatus in connection with the particular crimping machine shown for purposes of illustration. The feeding apparatus of the present invention might be used in connection with any machine for operating on a can where conditions exist similar to those involved in the above mentioned operation.

The object of the invention is to provide a simple, relatively inexpensive apparatus which shall be positive and efficient in its operation, for feeding cans to and from a crimping machine, or to and from other similar machines into or under which the cans in each case must remain stationary for a certain period while the crimping or other operation is performed.

A subordinate object of the invention is to provide a single feeding apparatus with duplicated feeding or forwarding devices whereby the cans may be fed from a single supply conveyor to two crimping or more machines, and from these machines to a single receiving conveyor, or other place of deposit.

A preferred embodiment of the apparatus is shown in the accompanying drawings, in connection with two crimping machines of known construction. In the drawings:

Fig. 1 is a plan view of the apparatus showing both feeding devices in full but only one of the crimping machines; the crimping machine for the lower position on the drawings being shown only fragmentarily for better illustration of the feeding arrangements.

Fig. 2 is a sectional elevation on line 2—2 of Fig. 1.

Fig. 3 is a vertical sectional view on line 3—3 of Fig. 5.

Fig. 4 is a sectional view on line 4—4 of Fig. 6.

Fig. 5 is a cross sectional view on line 5—5 of Fig. 1.

Fig. 6 is a fragmentary plan view of the parts of the feeding apparatus adjacent one of the crimping machines.

Fig. 7 is a fragmentary perspective view of the reciprocating structure and its associated mechanism whereby cans are fed to and from one of the crimping devices; and

Fig. 8 is a sectional plan on line 8—8 of Fig. 5.

It will simplify the understanding of the apparatus to briefly summarize its general structure and the several operations performed by the feeding apparatus before attempting to give a detailed description of the apparatus as illustrated in the drawings.

The two crimping machines A, A' are arranged face to face at any suitable distance apart. Two parallel conveyors are provided, on opposite sides of the crimping machines, a supply conveyor 19 which brings up the cans to be fed to the crimping machines and a receiving conveyor 25 to convey the cans away from said machines. In connection with each of the crimping machines there is a reciprocating structure (these structures being identical except that certain parts are reversely arranged in conformity with the reversed arrangement of the crimping machines). These two reciprocating structures are moved in unison to and from the crimping machine. A runway 11, 12 is provided extending from the supply conveyor to the discharging conveyor. The runway is formed with an offset which is arranged to position the cans successively under the crimping machine. That is, the feeding-in section of the runway is aligned with the operating head of the crimping machine. The feeding-out section of the runway is offset from this line providing a corner in which the cans are successively positioned while being operated upon by the crimping machine.

The reciprocating structure, which may be represented by the numerals 29, 29 performs the following functions: (1) It pushes each can, after the cap has been crimped to the head, from the corner between the offset portions of the runway into alignment with the cans in the feeding-out end of the runway. (2) It pushes a can from the supply conveyor into the feeding-in runway and forces the cans through this runway so as to bring another can under the crimping head. (3) It forces the cans through the feeding-out runway so as to deliver the last can in this section of the runway upon the discharge conveyor. (4) It interposes a stop against the cans on the supply conveyor which prevents them from passing the feeding-in runway until

the time has arrived for pushing another can into the runway; the conveyor, which runs continuously, sliding, at such times, under the arrested cans. (5) It sets in operation the crimping machine so that the crimping head descends upon the can, performs its crimping operation and then rises to release the can so that it may be pushed out from under the machine at the proper time as described. (6) In the case of the feeding mechanism associated with the crimping machine which first receives a can, (i. e. the upper mechanism—Fig. 1), it operates a stop which, functioning alternately with the stop just described, holds back a can which has passed the feeding-in runway of the first machine and is destined for the second machine, so as to position the next succeeding can in front of the feeding-in runway of the first machine until such can be pushed into the runway, whereupon the stop is withdrawn, releasing the can in which the stop was in contact so as to allow this can to be carried by the supply conveyor to the feeding mechanism for the second machine. That is, when the stops permit the supply conveyor to forward the cans, two cans are forwarded, one of which moves past the feeding-in runway of the first machine, but is held just beyond such runway so as to position the next can in alignment with said feeding-in runway. The first mentioned of the two cans goes to the second machine, the second can goes to the first machine. This same principle obviously could be applied to a feeding apparatus adapted for three or more crimping or other machines. In the two machine arrangement shown the cans destined for the second machine are arrested by a fixed stop with the forward can in alignment with the feeding-in runway of such second machine.

To give now a more detailed description of the entire apparatus shown in the drawings:

The crimping machine at the upper end of Fig. 1 is designated A. The other machine, in the lower part of the figure, is indicated fragmentarily at A'. It will be unnecessary to describe the crimping machine further than to say that it has a spindle B provided with a crimping head C. The spindle is movable vertically, as well as being revoluble, so that it can be brought down to and raised away from the cans successively positioned thereunder, the spindle rotating when the spindle is in the lower position. These movements are controlled by a link mechanism D.

In the drawings the cans are indicated by the letter E with exponents to indicate special positions.

A table 10 is arranged under the spindle B of the crimping machine and a runway for the cans is formed on the table by means of guide rails 11 and 12 which are formed with angular bends 13 and 14 (Fig. 6) so as to offset the two ends of sections of the runway, one from the other, forming a feeding-in section 15 and a feeding-out section 16, joined by a wider section 17 in line with the spindle of the crimping machine. Preferably the feeding-out section 16 is provided with a top guard member 18, the end of which stands over the can being operated upon so as to free the can from the crimping head if necessary. During the crimping operation the can being operated upon will bear against the transverse portion 13 of the guard rail 11.

The cans are brought up to the runway by a conveyor consisting of a continuously running chain 19 on a supporting structure 20 provided

with guard rails 21, 22, 23, 24 for guiding the cans.

At the other side of the apparatus is arranged, preferably, a receiving conveyor consisting of a belt 25 running on a suitable support 26. Guide rails 27, 28 may be provided at opposite sides of the conveyor. The belt 25 runs continuously.

The devices for effecting the movement of the cans through the run-way are carried upon or actuated by a reciprocating structure which is arranged under and moves in parallelism with the runway. This structure comprises a pair of rods 29, 29 slidably mounted in guides in a bracket 30 secured to the supporting structure 20 of the supply conveyor, the outer ends of which rods are united by a cross-head 31 and the inner ends secured to a cross beam 32 (Fig. 3). Pivoted to the cross-head 31 is a pitman 33 to which is pivoted a rock-arm 34 (Fig. 5) fulcrumed at 35 on a stationary part 36 of the apparatus and carrying at its lower end a roller 37 to bear on a cam 38 on a shaft 39 driven by a link belt 40 from the driving shaft 41 of the apparatus. A coiled tension spring 42 is engaged between the upper end of the rock arm 34 and a support 43 downwardly projecting from the structure 20. The upper end of the rock arm 34 is pivoted to a block 44 which is slidable on the pitman, for adjustment, and secured thereto by set screw 45. The cam 38 is shaped as shown so that the reciprocating structure will have rapid forward and backward movements with a dwell between such movements. This dwell gives additional time for performance of the crimping operation which must take place, of course, while the can is operated upon and is stationary.

The mechanisms associated with and actuated by the reciprocating structure just described are the following:

The transverse pusher arranged in line with the widened part 11 of the runway (Fig. 6) is a slide-way 46 in which is arranged a slide 47 (see also Fig. 4) which pushes against the can and also carries an upright post 48 provided with a horizontally arranged can pusher 49. Pivoted at 50 to the slide is a rock arm 51 fulcrumed at 52 on the table 10, the other end 53 of which is provided with a stud 54. A coiled spring 55 attached to the rock-arm 51 tends to retract the slide 47 and can pusher 49, that is tends to move the slide and pusher away from the can. Stud 54 on the other end of the rock-arm is engaged by a follower block 56 on a rod 57, one end of which is mounted in a guide 58 on the table and the other end of which is secured to an upwardly extending arm 59 on the cross piece 32 (Figs. 3 and 7) of the reciprocating structure. In Figs. 1, 6 and 7 the parts of the mechanism are in the positions which they have assumed in pushing the can E' which was at the end of the feeding-in runway section 15 and against the stop 13, to its position in alignment with the cans in the feeding-out section 16 of the runway. The rearward movement of the reciprocating structure has brought about this movement of pusher 49 through engagement of block 56 with stud 54. When the reciprocating structure moves forwardly spring 55 retracts the slide 47 and pusher 49 so as to make place under the crimping machine for the next can to be operated upon, that is, can E², (Figs. 1 and 6).

The pusher for moving the cans into and through the feeding-in runway.—A cross-head 60 is secured to rods 29 of the reciprocating structure by means of bosses 61 on the rods and nuts 62. The cross-head is formed with a curved arm 75

63 terminating in a vertical plate 64 which normally stands to the right of conveyor 19 in alignment with the feeding-in section 15 of the runway, as shown in Fig. 1. With the forward movement 5 of the reciprocating structure this pusher 63, 64 is brought to bear against the can E³ on conveyor 19 in line with the runway. During this portion of the forward movement, the block 56 is carried forward a distance sufficient to release 10 the rocker arm 51 and permit the slide 47 to assume its retracted position. The continued forward movement of the reciprocating structure moves the can E³ from the conveyor into the runway, pushing ahead of it the line of cans in the 15 runway so as to bring can E² under the spindle of the crimping machine.

The pusher 63—64 is provided with a skirt or stop plate 65, at right angles to plate 64, which acts as a stop to prevent the continued forward 20 movement of the cans approaching the runway on conveyor 19 during time that the pusher is in contact with can E³. During this period the can E⁴ (Fig. 1) will bear against the stop plate 65, the conveyor sliding under this can and any other 25 cans that may be stopped in their forward movement.

A stop is also provided to prevent the can E³ from moving out of its position in alignment with the feeding-in runway; and where, as in the installation 30 illustrated, the conveyor 19 is intended to supply cans to two crimping machines, the arresting of the can E³ is brought about by stopping the movement of the can E⁵ ahead of it, as shown in Fig. 1. That is, when released by the stop plate 65 two cans are allowed to move forward, the can E⁵ to a position beyond the runway and the can E³ to a position in alignment with the runway. The movement of these two cans is arrested by a horizontal stop rod 66 which is 35 secured to an angular support 67 on the cross piece 32 of the reciprocating structure, this support extending through a slot 68 in the table. A similar slot 69 is provided for the arm 59 on the other side of cross piece 32.

45 As the reciprocating structure is given its forward movement stop 66 is withdrawn from can E⁵, which is then moved by the conveyor to the feeding mechanism for the crimping machine A¹, and two other cans E⁴ and E⁵ (Fig. 1) are advanced by the conveyor as soon as can E⁴ has been released by the stop plate 65.

The pusher for the cans in the feeding-out runway.—These cans are moved longitudinally through the runway by the pusher 63, 64 through 50 the movement of the cans in the feeding-in runway, but it is also desirable to provide a positive pushing device for moving the cans in the feeding-out runway section which will operate against the cans along the center line of their travel. To 55 this end the support 67 is formed with a horizontally extending portion 70 formed with a slot 71 into which projects a stud 72 on a sliding member 73 (Fig. 8), which is guided so as to move on the lower guard rail 74 of the can runway (Fig. 65 7); a tongue and groove connection being preferably provided as indicated at 75 (Fig. 3). The stud 72 extends through a slot 76 in a stationary guide member 77 supported on the runway structure. The purpose of this arrangement is to provide a lost-motion connection between the slide 70 73 which slide acts as a pusher against the cans in the feeding-out runway section, and the reciprocating structure. As the reciprocating structure moves forwardly there is no movement at 75 first of the pusher 73. When the horizontal

member 70 has moved forward far enough so that contact is made with the stud at the right-hand end of slot 71 (Fig. 8), the pusher 73 will be carried forward sufficiently to move the cans in the feeding-out runway the distance of one can's width, pushing a can upon the receiving conveyor 25. On the return movement of the reciprocating structure the pusher 73 remains in position back of the can being operated upon by the crimping device, and thereby aids in keeping the can 10 in proper position during this operation, until contact is made between the horizontal member 70 and stud 72 at the left-hand end of slot 71 (Fig. 8), whereupon the pusher is retracted before the slide 47 and pusher 49 are operated to 15 shift the can into the feeding-out runway.

Stops over the receiving conveyor.—Arranged above the receiving conveyor 25 near the place where the feeding-out runway terminates is an angular stop member 78 pivoted at 79 to a bracket 20 80, a tension coiled spring 81 being interposed between the stop device and the bracket. The function of this device is to align the cans on the conveyor belt 25. It is made spring pressed so that it can yield if the cans, through accidental 25 mal-adjustment of the apparatus are pushed too far. With this contingency in view a table 82 is arranged opposite the runway. In fact the receiving conveyor is an optional feature. The cans could be delivered upon a table and removed 30 from there by hand.

Actuation of the crimping machine.—The rod 51 which actuates the transverse pusher 49 is provided with a cam block 83 which engages a cam 84 which, through movement of the link 35 mechanism D puts the crimping machine into and out of operation at the proper times. This controlling mechanism in itself is old. The present invention contemplates its actuation through the engagement of the cams 83, 84 as described, brought about by the movement of the same reciprocating structure that feeds the cans to and from the machine.

Feed to the second crimping machine.—The feeding apparatus for the crimping machine A' 45 is, in substance, the same as the feeding apparatus, above described for the crimping machine A except that as the crimping machines face each other certain of the operative parts of the apparatus are in reverse position, as will be 50 clear from the drawings. In place, however, of the movable stop 66, the feeding apparatus for machine A' has a fixed stop 85 (Fig. 1) for arresting the can E⁷ in alignment with the cans in the feeding-in runway. If the apparatus were 55 designed to feed three machines, the feeding mechanism for the second machine would be provided with a movable stop instead of a fixed stop.

Other modifications will occur to those skilled 60 in the art; and it is to be understood that the intention is to cover by patent all variations and modifications within the scope of the appended claims.

I claim:

1. In combination with a machine for operating on cans, apparatus for feeding cans to said machine comprising: a supply conveyor; a runway having feeding-in and feeding-out sections offset with respect to each other at the place 70 of operation of said machine on the can; and mechanism for moving cans intermittently from the feeding-in section to the feeding-out section of the runway, which also moves cans from said conveyor into the feeding-in section of the run- 75

way and pushes cans one against another through said runway.

2. In combination with a machine for operating on cans, apparatus for feeding cans to said machine comprising: a supply conveyor, a runway having feeding-in and feeding-out sections offset with respect to each other at the place of operation of said machine on the cans; and mechanism for moving cans intermittently from the feeding-in section to the feeding-out section of the runway, which also moves cans from said conveyor into the feeding-in section of the runway and pushes cans in groups through said runway and which includes a pusher that operates directly on the group of cans in the feeding-out section of the runway.

3. In combination with a machine for operating on cans, apparatus for feeding cans to said machine comprising: a supply conveyor; a runway having feeding-in and feeding-out sections offset with respect to each other at the place of operation of said machine on the cans; and mechanism for moving cans intermittently from the feeding-in section to the feeding-out section of the runway, which also moves cans from said conveyor into the feeding-in section of the runway and pushes cans through said runway and which includes a pusher that operates directly on the cans in the feeding-out section of the runway and stands back of the cans while being operated on by said machine.

4. In combination with a machine for operating on cans, apparatus for feeding cans to said machine comprising: a supply conveyor; a runway having feeding-in and feeding-out sections offset with respect to each other at the place of operation of said machine on the cans; and mechanism for moving cans intermittently from the feeding-in section to the feeding-out section of the runway, which also moves cans from said conveyor into the feeding-in section of the runway and pushes cans through said runway; said mechanism being provided with a stop for arresting the forwarding of the cans by the conveyor while a can is being moved from the conveyor into the feeding-in runway.

5. In combination with a machine for operating on cans, apparatus for feeding cans to said machine comprising: a supply conveyor; a runway having feeding-in and feeding-out sections offset with respect to each other at the place of operation of said machine on the cans; and mechanism for moving cans intermittently from the feeding-in section to the feeding-out section of the runway, which moves cans from said conveyor into the feeding-in section of the runway, pushes cans one against another through said runway, and also controls the operation of said machine.

6. In combination with a machine for operating on cans, apparatus for feeding cans to said machine comprising: a supply conveyor; a runway having feeding-in and feeding-out sections offset with respect to each other at the place of operation of said machine on the cans; mechanism for moving cans intermittently from the feeding-in section to the feeding-out section of the runway, which moves cans from said conveyor into the feeding-in section of the runway and pushes cans in groups through said runway; and a discharge conveyor to receive the cans from the feeding-out section of the runway.

7. In combination with a machine for operating on cans, apparatus for feeding cans to said machine comprising: a supply conveyor; a run-

way having feeding-in and feeding-out sections offset with respect to each other to provide a stop at right angles to the runway for positioning the cans for operation upon by said machine; and mechanism which moves the cans intermittently from said stop into line with the cans in the feeding-out runway, which moves the cans from said conveyor into the feeding-in section of the runway and which pushes the cans in groups through said runway.

8. In apparatus for feeding cans, the combination of a continuously moving supply conveyor; a runway transversely arranged in respect thereto; a stop for arresting the can on the conveyor which has passed the runway, so as to position a succeeding can in line with the runway; and mechanism for pushing the last mentioned can into the runway, for releasing the other can, and for arresting the forward movement of the next can on the conveyor approaching the runway.

9. In apparatus for feeding cans, the combination of a runway having feeding-in and feeding-out sections the inner ends of which are adjacent and offset with respect to each other; an actuating structure which reciprocates in parallelism with said runway; a pusher operated by said actuating structure for moving the cans intermittently from the inner end of the feeding-in section of the runway into alignment with the cans in the feeding-out section of the runway; a pusher for moving the cans longitudinally through the feeding-in runway; and a separate pusher on the actuating structure which is brought to bear upon and moves the cans in the feeding-out runway section.

10. In apparatus for feeding cans, the combination of a runway having feeding-in and feeding-out sections the inner ends of which are adjacent and offset with respect to each other; an actuating structure which reciprocates in parallelism with said runway; a pusher operated by said actuating structure for moving the cans intermittently from the inner end of the feeding-in section of the runway into alignment with the cans in the feeding-out section of the runway; a pusher for moving the cans longitudinally through the feeding-in runway; and a separate pusher having a lost motion connection with the actuating structure which is brought to bear upon and moves the cans in the feeding-out section of the runway.

11. In apparatus for feeding cans, the combination of a conveyor; a runway transversely arranged with respect to the conveyor; a reciprocating device which moves in parallelism with the runway; a pusher on said device for moving cans from the conveyor into the runway; a stop on the pusher which extends across the conveyor during the movements of the pusher to arrest the forward movement of the next can approaching the runway; and a stop to arrest the movement of a can on the conveyor which has passed the runway, said stop being arranged on the reciprocating device so as to free said can during the forward movement of the pusher.

12. In apparatus for feeding cans, the combination of a conveyor; a runway consisting of feeding-in and feeding-out sections offset with respect to each other; and actuating structure reciprocating in parallelism with the runway; a pusher on said actuating structure for moving cans from the conveyor into one end of the feeding-in section of the runway; a stop on said pusher to arrest the forward movement of the next can on the conveyor approaching the runway; and mechanism, operated by said actuating structure for

pushing cans from the other end of the feeding-in section of the runway into alignment with the cans in the feeding-out section.

13. In apparatus for feeding cans, the combination of a conveyor; a runway consisting of feeding-in and feeding-out sections offset with respect to each other; an actuating structure reciprocating in parallelism with the runway; a pusher on said actuating structure for moving cans from the conveyor into one end of the feeding-in section of the runway; a stop on said pusher to arrest the forward movement of the next can on the conveyor approaching the runway; mechanism operated by the actuating structure for pushing cans from the other end of the feeding-in section of the runway into alignment with the cans in the feeding-out section; and a pusher, having a lost motion connection with the actuating structure, which acts directly upon the cans in the feeding-out runway section.

14. In apparatus for feeding cans, the combination of a conveyor; a runway consisting of feeding-in and feeding-out sections offset with respect to each other; an actuating structure reciprocating in parallelism with the runway; a pusher on said actuating structure for moving cans from the conveyor into one end of the feeding-in section of the runway; a stop on said pusher to arrest the forward movement of the next can on the conveyor approaching the runway; mechanism operated by the actuating device for pushing cans from the other end of the feeding-in section of the runway into alignment with the cans in the feeding-out section; and a stop on the actuating structure which during the operation of said pusher, arrests the forward movement of a can on the conveyor which has passed the runway and is withdrawn from said can when the can ahead of it has been pushed into the runway.

15. In apparatus for feeding cans, the combination of a conveyor; a runway consisting of feeding-in and feeding-out sections offset with respect to each other; an actuating structure reciprocating in parallelism with the runway; a pusher on said actuating structure for moving cans from the conveyor into one end of the feeding-in section of the runway; a stop on said pusher to arrest the forward movement of the next can on the conveyor approaching the runway; mechanism operated by the actuating device for pushing cans from the other end of the feeding-in section of the runway into alignment with the cans in the feeding-out section; a pusher having a lost motion connection with said actuating structure which is brought to bear directly on the cans in the feeding-out section of the runway; and a stop for arresting a can on the conveyor which has passed the runway but which releases said can when the can ahead of it is pushed into the runway.

16. In combination with a machine for operating on cans, apparatus for feeding the cans to said machine comprising: a continuously moving conveyor; a runway transversely arranged

thereto having feeding-in and feeding-out sections the adjacent ends of which are offset at the place at which the can is operated upon by said machine; an actuating structure which reciprocates in parallelism with the runway; a pusher on said structure for moving cans from the conveyor into one end of the feeding-in section of the runway; a stop on said pusher which extends across the conveyor and stops the forward movement of cans approaching the runway; mechanism operated by said actuating structure for moving the cans intermittently from the other end of the feeding-in section of the runway into alignment with the cans in the feeding-out section; and means on said actuating structure for controlling the operation of said machine.

17. In combination with a machine for operating on cans, apparatus for feeding the cans to said machine comprising: a continuously moving conveyor; a runway transversely arranged thereto having feeding-in and feeding-out sections the adjacent ends of which are offset at the place at which the cans are operated upon by the machine; an actuating structure which reciprocates in parallelism with the runway; a pusher on said structure for moving cans from the conveyor into one end of the feeding-in section of the runway; a stop on said pusher which extends across the conveyor and stops the forward movement of cans approaching the runway; mechanism operated by said actuating structure for moving cans intermittently from the other end of the feeding-in section of the runway into alignment with the cans in the feeding-out section; means on said actuating structure for controlling the operation of said machine; and a pusher having a lost motion connection with said actuating structure which is brought to bear directly upon the cans in the feeding-out section of the runway.

18. In combination with a machine for operating on cans, apparatus for feeding the cans to said machine comprising: a continuously moving conveyor; a runway transversely arranged thereto having feeding-in and feeding-out sections the adjacent ends of which are offset at the place at which the cans are operated upon by the machine; an actuating structure which reciprocates in parallelism with the runway; a pusher on said structure for moving cans from the conveyor into one end of the feeding-in section of the runway; a stop on said pusher which extends across the conveyor and stops the forward movement of cans approaching the runway; mechanism operated by said actuating structure for moving cans intermittently from the other end of the feeding-in section of the runway into alignment with the cans in the feeding-out section; means on said actuating structure for controlling the operation of said machine; and a conveyor for receiving cans from the feeding-out section of the runway.

CERTIFICATE OF CORRECTION.

Patent No. 2,029,558.

February 4, 1936.

GEORGE W. CHALMERS.

It is hereby certified that error appears in the printed specification of the above numbered patent requiring correction as follows: Page 3, first column, line 53, for "cams" read cans; page 4, first column, line 27, claim 3, after "cams" insert the words in groups; line 29, same claim, before "cams" insert the words group of; page 5, second column, line 13, claim 16, for "other" read inner; and that the said Letters Patent should be read with these corrections therein that the same may conform to the record of the case in the Patent Office.

Signed and sealed this 10th day of March, A. D. 1936.

Leslie Frazer

(Seal)

Acting Commissioner of Patents.
